(57) **CLAIM**

The ornamental design for a climbing frame, as shown and described.

DESCRIPTION

FIG. 1 is a front, left side isometric view of our new design for a climbing frame.

FIG. 2 is a top side plan view of FIG. 1.

FIG. 3 is a bottom side plan view of FIG. 1.

FIG. 4 is a front side elevation view of FIG. 1.

FIG. 5 is a back side elevation view of FIG. 1.

FIG. 6 is a right side elevation view of FIG. 1; and,

FIG. 7 is a left side elevation view of FIG. 1.

The features shown in broken lines in the drawing depict portions of the climbing frame and environmental subject matter only, and form no part of the claimed design.

1 Claim, 7 Drawing Sheets
